The ornamental design for a regenerative filter, as shown and described.

DESCRIPTION

FIG. 1 is a perspective view of a regenerative filter;
 FIG. 2 is a front elevational view thereof;
 FIG. 3 is a rear elevational view thereof;
 FIG. 4 is a right side elevational view thereof;
 FIG. 5 is a left side elevational view thereof;
 FIG. 6 is a top plan view thereof;
 FIG. 7 is a bottom plan view thereof;
 FIG. 8 is a perspective view of a second embodiment thereof;
 FIG. 9 is a front elevational view of a second embodiment thereof;
 FIG. 10 is a rear elevational view of a second embodiment thereof;
 FIG. 11 is a right side elevational view of a second embodiment thereof;
 FIG. 12 is a left side elevational view of a second embodiment thereof;
 FIG. 13 is a top plan view of a second embodiment thereof;
 FIG. 14 is a bottom plan view of a second embodiment thereof;
 FIG. 15 is a perspective view of a third embodiment thereof;
 FIG. 16 is a front elevational view of a third embodiment thereof;
 FIG. 17 is a rear elevational view of a third embodiment thereof;
 FIG. 18 is a right side elevational view of a third embodiment thereof;
 FIG. 19 is a left side elevational view of a third embodiment thereof;
 FIG. 20 is a top plan view of a third embodiment thereof;
 FIG. 21 is a bottom plan view of a third embodiment thereof;
 FIG. 22 is a perspective view of a fourth embodiment thereof;
 FIG. 23 is a front elevational view of a fourth embodiment thereof;
 FIG. 24 is a rear elevational view of a fourth embodiment thereof;
 FIG. 25 is a right side elevational view of a fourth embodiment thereof;
 FIG. 26 is a left side elevational view of a fourth embodiment thereof;
 FIG. 27 is a top plan view of a fourth embodiment thereof;
 FIG. 28 is a bottom plan view of a fourth embodiment thereof;
 FIG. 29 is a perspective view of a fifth embodiment thereof;
 FIG. 30 is a front elevational view of a fifth embodiment thereof;
 FIG. 31 is a rear elevational view of a fifth embodiment thereof;
 FIG. 32 is a right side elevational view of a fifth embodiment thereof;
 FIG. 33 is a left side elevational view of a fifth embodiment thereof;
 FIG. 34 is a top plan view of a fifth embodiment thereof;
 FIG. 35 is a bottom plan view of a fifth embodiment thereof;

FIG. 36 is a perspective view of a sixth embodiment thereof;
FIG. 37 is a front elevational view of a sixth embodiment thereof;

FIG. 38 is a rear elevational view of a sixth embodiment thereof;

FIG. 39 is a right side elevational view of a sixth embodiment thereof;

FIG. 40 is a left side elevational view of a sixth embodiment thereof;

FIG. 41 is a top plan view of a sixth embodiment thereof; and,
